UNITED STATES PATENT OFFICE.

LOUIS MARX, OF NEW YORK, N. Y.

TOY.

Application filed June 14, 1924. Serial No. 719,962.

This invention relates to a toy, and more particularly to a wheeled toy or toy vehicle; and has special reference to the provision of a toy vehicle simulating in structure and 5 operation a fuel-consuming wheeled apparatus.

The prime objects of my present invention include the provision of a toy constructed in simulation of a fuel-consuming apparatus 10 or structure such as a fire engine, locomotive or automobile, and having means for the generation or production of an emission of sparks in semblance of a fuel-consuming activity; the further provision of a mechanically 15 operated wheeled toy in which a motor mechanism is provided for propelling the toy and in which the means for generating or producing the emission of sparks is actuated from the running gear of the toy 20 or the motor mechanism; and the still further provision of a toy of this nature in which a pyrophoric body is employed as the spark-producing means.

To the accomplishment of the foregoing 25 and such other objects as may hereinafter appear, my invention consists in the elements and their relation one to the other, as hereinafter particularly described and sought to be defined in the claims; reference 30 being had to the accompanying drawings, which show preferred embodiments of my invention, and in which:

Fig. 1 is a view in perspective of one 35 form of my invention showing the principles of the same embodied in a fire engine,
Fig. 2 is a fragmentary view thereof taken in longitudinal cross-section,

Fig. 3 is a cross-sectional view taken on the line 3—3, Fig. 2,

Fig. 4 is a view in perspective of another 40 form of my invention showing the principles of the same embodied in a fuel motor operated vehicle,

Fig. 5 is an enlarged fragmentary view 45 thereof with parts shown in section, and

Fig. 6 is a bottom plan view thereof.

Referring now more in detail to the drawings, and having reference to Figs. 1 to 3 thereof, I show my invention applied to a 50 wheeled vehicle of the fire engine type, the said wheeled vehicle comprising a vehicle body 10 made of sheet material, running gear therefor including the front wheels 11 and the rear wheels 12, the vehicle including 55 means for simulating a fuel-consuming structure such as the cylinder 13 terminat-

ing in a smoke orifice or stack 14 in semblance of a vehicle of the fire engine type.

For propelling the vehicle along a support, there is provided motor mechanism 60 which is geared to the rear wheels 12, and in the preferred form of the invention I utilize a spring motor generally designated as 15 and comprising a drum 16 loose on a shaft 17, which drum fixedly carries a gear 18 meshing with a pinion 19 fixed to the rear axle 20, to which one or both of the wheels 12 may be secured; and encircling the drum 16 there is provided the spring motor 21 one end of which is anchored to 70 the drum and the other end of which is anchored, as at 22, to a ratchet 23 fixed to the shaft 17, the said ratchet cooperating with a spring pawl 24 for holding the spring motor in energized condition when the same 75 is wound by means of the finger grip 25 fixedly carried by the shaft 17.

For simulating the fuel-consuming operation of the structure 13, my invention includes the provision of means associated 80 with the structure 13 for generating or producing an emission of sparks in striking resemblance to the production of sparks incident to and ordinarily attending fuel consumption. The spark producing means or 85 device preferably comprises a pyrophoric body 26 such as ferro-cerium held in a support 27 which is resiliently urged by means of a spring 28 into contacting engagement with a friction wheel 29 which is connected 90 for operation by the running gear of the vehicle or the motor mechanism 15. To effect the producing of a copious emission of sparks when the vehicle is propelled, the spark producing means is arranged close to 95 the opening or mouth of the stack 14 as clearly shown in Figs. 2 and 3 of the drawings; and the mechanism for operating the spark producing means is preferably housed by the cylinder 13, the said mechanism comprising a speed increasing gear train generally designated as 30 carried by a bracketed structure 31 and including the pinion 32 meshing with the gear 18, which pinion is fixed to a shaft 33 carrying a gear 34, which gear in turn meshes with the pinion of a combined gear and pinion 35, the gear of which meshes with a pinion 36 fixed to the shaft 37 which carries the friction wheel 29. The friction wheel may be made in any desired way, and preferably includes a sand 100 paper or emory cloth surface which when

105
110

engaged by the pyrophoric body will produce a copious flow of sparks moving through the mouth of the stack 14, as clearly shown in Figs. 1 and 2 of the drawings.

Referring now to Figs. 4-6 of the drawings, I show the principles of my invention applied to a motor-operated vehicle such as an automobile, the operation of the motor being simulated by the production or emission of sparks. In this form of my invention the vehicle comprises the body 38 made of sheet material of any appropriate design mounted on the front wheels 39 (one of which is shown in the drawings) and the rear wheels 40, and a spring motor mechanism for propelling the vehicle which includes the spring motor 41 having a construction similar to that heretofore described in connection with Figs. 1-3 of the drawings, a gear 42 fixed to the motor shaft meshing with a pinion 43 fixed to a shaft 44, said shaft carrying the gear 45 which in turn meshes with a pinion 46 fixed to the rear axle 47 to which one or both of the wheels 40 is or are fixedly secured.

In this form of the invention, the device for producing the spark emission is associated with a portion simulating the exhaust feature of an automobile motor, and comprises a member 48 carrying a pyrophoric body 49 which may be spring pressed or gravitationally held in contact with a friction wheel 50, and one end of the said member may be shaped in the form of a cylinder 51 resembling the exhaust passage of a motor. The friction wheel 50 is driven from the running gear or motor 41 by means of a pinion 52 fixed to the shaft 53 which carries the wheel 50, said pinion meshing with a gear 54 fixed on the axle shaft 47. With this construction it will be apparent that when the vehicle is propelled along the ground or other support, the sparks produced will fly in the direction of the exhaust, producing in striking resemblance the appearance of sparks emanating from the exhaust passage.

The manner of making and using the toy of my invention will in the main be fully apparent from the above detailed description thereof. It will be further apparent that numerous changes and modifications may be

made in the structure disclosed without departing from the spirit of the invention, defined in the following claims.

I claim:

1. A toy vehicle comprising a vehicle body, running gear therefor, means simulating part of a fuel-consuming structure, and devices associated with said means for producing an emission of sparks in semblance of fuel-consuming activity of such means, said devices comprising a pyrophoric body, a friction wheel arranged to be frictionally engaged by the pyrophoric body, and motion multiplying gearing connecting the said running gear with the friction wheel.

2. A toy vehicle comprising a vehicle body, motor mechanism for propelling the same, means simulating part of a fuel-consuming structure, and devices associated with said means for producing an emission of sparks in semblance of a fuel-consuming activity of said means, said devices comprising a pyrophoric body, a friction wheel arranged to be frictionally engaged by the pyrophoric body, and motion-multiplying gearing connecting the said motor mechanism with the friction wheel.

3. A toy vehicle comprising a vehicle body, motor mechanism for propelling the same, means simulating part of a fuel-consuming structure, and a device associated with said means and including a pyrophoric body and a friction wheel operated by said motor mechanism arranged to be engaged by said pyrophoric body for producing an emission of sparks in semblance of the fuel consumption activity.

4. A toy vehicle comprising a vehicle body, running gear therefor, means simulating part of a fuel-consuming structure, and a device associated with said means and including a pyrophoric body and a friction wheel connected to said running gear and arranged to be engaged by said pyrophoric body for producing an emission of sparks in semblance of a fuel-consuming activity.

Signed at New York city in the county of New York and State of New York, this 13th day of June, A. D. 1924.

LOUIS MARX.
